(57) **CLAIM**

I claim the ornamental design for a hinged case, as shown and described.

DESCRIPTION

FIG. 1 is a top front left perspective view of the hinged case.
FIG. 2 is a bottom front left perspective view of the hinged case.

FIG. 3 is a front view of the hinged case.

FIG. 4 is a rear view of the hinged case.

FIG. 5 is a top view of the hinged case.

FIG. 6 is a bottom view of the hinged case.

FIG. 7 is a right side view of the hinged case; and,

FIG. 8 is a left side view of the hinged case.

The broken line showings of a zipper teeth, a zipper pull tab, and portion of a zipper slider do not form portions of the claimed design.
